UNITED STATES PATENT OFFICE.

JOHN J. DAVIN AND FRANK J. JICHA, OF CHICAGO, ILLINOIS.

PARACHUTE.

Application filed February 12, 1924. Serial No. 692,384.

To all whom it may concern:

Be it known that we, JOHN J. DAVIN and FRANK J. JICHA, citizens of the United States, residing at Chicago, in the county of Cook and State of Illinois, have invented certain new and useful Improvements in Parachutes, of which the following is a specification.

Our said invention relates to parachutes and it is an object of the same to provide a parachute which shall be simple in construction and very certain and safe in its operation. A further object is to provide a parachute which shall have a true hemispherical form and therefore a greater spread.

Referring to the accompanying drawings, which are made a part hereof and on which similar reference characters indicate similar parts,

20 Figure 1 is an elevation of our device in open position,

Figure 2, a similar view in closed position,

Figure 3, an elevation showing another form of pack,

25 Figure 4, a vertical section of the same,

Figure 5 illustrates a sustaining means for the hanging parachute by which it is secured to a dirigible an aeroplane or a balloon, and

30 Figure 6 is an elevation of a girdle in position on the lower part of the parachute.

In the drawings reference character 10 indicates the bottom ring of the parachute to which are attached two sets of lines 11 and 12. These lines are attached at their outer ends to the frame of the parachute, the lines 12 passing through eyes 13 on arms 14 and thence to eyes 15 at the upper ends of the outer auxiliary arms 16 which are pivoted 35 at 17 to the main arms 14. The lines 11 are connected to the outer ends of the arms 16 at 18 by means of eyelets or other suitable devices. The outer arms 16 are held in spaced relation to the main arms 14 when the para-

40 chute is closed by means of blocks 19 and the arms 14 are pivoted at their lower ends to a hub 20 provided with grooves to hold the arms in spaced relation. A post 21 extends up from the hub and a spacer 22 near the 45 upper end of the post serves to hold the upper ends of arm sections 16 away from the post. The cloth 23 of the parachute is secured to the upper end of the post and hangs down from the same in the folded position

of the parachute as illustrated in Figures 2 55 and 4 in a short pack in which the depending skirt of the cloth is folded between the post and the arms in a loop as indicated at 24 in Figure 4 or else in a long pack as indicated at 25 in Figure 3, where the cloth remains on the outside of the arms.

It will be seen that the lines 12 are always held tight in the operation of the device so that the weight of the operator when the parachute is put into use is transmitted directly through the eyes 13 to the upper ends 65 of the rib sections 15 pivoted on main arms 14 outside the circle of pivots on hub 20 and outside the circle of eyes 15, the weight of the operator thus acting very effectually to 70 open the parachute. The lines 11 are loose at this time and until the parachute is fully opened at which time the eyes 15 approach close to eyes 13, as shown in dotted lines in Figure 4, while the lines 11 secured to what 75 are now the outer ends of the compound arms are also drawn taut as may be seen in Figure 1.

For suspending the parachute on an aero-plane, a dirigible or a balloon, a bracket 26 80 may be secured thereto by screws or otherwise this bracket having at one corner a pivot 27 for a bent hook 28 on which may rest a loop 29 at the upper end of the parachute. The hook is normally held in closed 85 position by means of a spring 30 but may be instantly released by a pull on the cord 31 and will ordinarily be so arranged that the mere weight of the operator will disconnect the parachute if for any reason the cord 90 should not operate the hook with sufficient quickness.

In Figure 6 we have indicated a girdle 32 provided with shoulder straps 33 and a seat composed of front straps 34 and a rear 95 strap 35 all of which parts are fastened together by buckles as shown. The girdle is provided with cords 36 converging at 37 and either secured to the ring 10 at their upper ends or if preferred separate cords 100 may be provided at 38 for connecting the ends of the cords 36 to the ring 10.

It will be obvious to those skilled in the art that various modifications may be made in our device without departing from the spirit of the invention and therefore we do not desire to limit ourselves to the specific device shown in the drawings and described

in the specification, but only as indicated in the appended claims.

Having thus fully described our said invention, what we claim as new and desire 5 to secure by Letters Patent, is:

1. A parachute comprising a post, a cloth covering centrally secured to the top of the post, a hub secured to the post at a distance from the top, a series of main arms pivoted 10 to the hub, auxiliary arms pivoted to the outer ends of the main arms, and means for holding the outer ends of the auxiliary arms in spaced relation to the main arms when the parachute is closed, and means for securing the outer edge of the cloth to the auxiliary arms adjacent to their outer ends, substantially as set forth.
2. A parachute comprising a post, a hub secured thereto, a series of main arms pivoted 20 to the hub, auxiliary arms pivoted to the outer ends of the main ribs, means for holding the lower ends of the auxiliary arms in spaced relation to the main arms when the parachute is closed, and a spacer near 25 the upper end of the post to hold the auxiliary arms spaced therefrom, substantially as set forth.
3. A parachute comprising a post, a hub secured thereto, a series of main arms pivoted 30 to the hub, auxiliary arms pivoted to the outer ends of the main ribs, means for holding the outer ends of the auxiliary arms in spaced relation to the main arms when the parachute is closed, normally tight lines 35 passing through eyes approximately midway of the main arms and secured to one end of the auxiliary ribs, and normally loose lines secured to the outer ends of the auxiliary arms, substantially as set forth.
4. A parachute comprising a post, a hub secured thereto, main arms pivoted on the hub, auxiliary ribs pivoted approximately 40 midway of their length to the main arms, means for holding the auxiliary ribs in spaced relation to the post and inclined 45 relatively to said main arms when in closed position the folds of the closed parachute being adapted to be received between the series of ribs and the post, substantially as 50 set forth.
5. The combination with a flying machine, of a suspending device for parachutes comprising a bracket, secured to the flying machine a hook pivotally mounted on the bracket and having an end adapted to bear 55 against one side of the bracket said end supporting a hook secured to the upper end of the parachute, a spring for holding the hook in closed position, and manually operated

means for releasing the hook, substantially as set forth.

6. A parachute comprising a post, a set of arms pivotally connected to the post at their lower ends, auxiliary arms pivoted intermediate their ends to the main ribs, and 65 means for holding the outer ends of the auxiliary arms spaced away from the main arms when the parachute is closed, substantially as set forth.

7. A parachute comprising a post, a set of 70 arms pivotally connected to the post at their lower ends, auxiliary ribs pivoted intermediate their ends to the main arms, means for holding the outer ends of the auxiliary arms spaced away from the main arms 75 when the parachute is closed, and lines connected to the inner ends of the auxiliary arms whereby the weight of the operator tends to open the parachute, substantially as set forth.

8. A parachute comprising a post, a hub secured thereto, a series of main arms pivoted to the hub, auxiliary ribs pivoted to the outer ends of the main arms, means for holding the lower ends of the auxiliary 85 arms in spaced relation to the main arms when the parachute is closed, a spacer near the upper end of the post to hold the auxiliary arms spaced therefrom, and normally tight lines passing through guides on the 90 main arms and secured to the outer ends of the auxiliary arms whereby the weight of the operator tends to open the parachute, substantially as set forth.

9. In a parachute, a post, a cloth covering centrally secured at the top of the post, and arms connected to the outer edge of the cloth said arms being swingingly mounted on the post at a distance from the top, and said cloth covering being otherwise free of support, substantially as set forth.

10. In a parachute, a post, a cloth covering centrally secured at the top of the post, and jointed arms connected to the outer edge of the cloth said arms being swingingly mounted on the post at a distance from the top, and said cloth covering being otherwise free of support, substantially as set forth.

In witness whereof, we have hereunto set 110 our hands and seals at Chicago, Illinois, this 24th day of January, A. D. nineteen hundred and twenty-four.

JOHN J. DAVIN. [L.S.]
FRANK J. JICHA. [L.S.]
